COOLING OF CHROMIUM PLATING SOLUTION

Edgar A. Hahn, Grosse Pointe Park, Mich., assignor to Lyon Incorporated, Detroit, Mich., a corporation of Delaware

Filed Mar. 17, 1958, Ser. No. 722,063

5 Claims. (Cl. 62—100)

The present invention relates broadly to the art of plating, and is more particularly concerned with a novel method of accomplishing temperature control in chromium and like plating baths.

It is known that during electrolysis of a chromic acid plating solution there is a substantial heat input to the solution, and that a rise in the solution temperature requires a current increase in order to maintain proper plating conditions. Accordingly, it is customary practice in a continuous plating line, in order to maintain the bath at the desired temperature, to pass the heated solution through heat exchange means, and by reduction of solution temperature, assure formation of a chromium deposit having the desired characteristics.

The cooling fluid generally employed in the heat exchanger is water from a municipal supply system, and while during the major portion of the year the temperature of the water is normally sufficiently low to provide the desired cooling, in many locations during the summer months the water temperature is such that it performs rather poorly as a coolant. The result is that it has often been necessary under these conditions to shut down the plating line until sufficiently cool water is obtained. While it would appear that a sufficiently large heat exchanger could be employed, this has not proven expedient from a production standpoint.

It is therefore an important aim of the present to provide a temperature reduction method for plating solutions which is essentially continuous in operation and does not cause substantial interruptions to the plating procedures.

Another object of this invention lies in the provision of a cooling method for chromium plating solutions which is productive of extremely accurate results and may be performed in a minimum length of time by relatively unskilled personnel.

A further object of the invention is to provide a cooling method for a plating bath which comprises removing from the bath relatively warm solution, evaporating said solution to a predetermined point to reduce the temperature thereof, and returning the reduced temperature solution to the bath, the vapor portion therefrom being condensed and the condensate employed in connection with the rinsing operation.

A still further object of the present invention lies in the provision of apparatus for cooling chromium and like plating solutions, comprising a tank containing relatively warm plating solution, evaporator means receiving the relatively warm solution and reducing the temperature of said solution by removing the low temperature vapor portion, and means connecting the tank and evaporator means feeding the relatively warm solution to the evaporator means and returning the relatively cooler solution to the plating tank.

A still further object of this invention is to provide cooling apparatus of the foregoing character, and which may further include condensing means receiving the low

2

temperature vapor portion of the solution from the evaporator means and passing the condensate to a container for use in connection with the rinsing operation.

Other objects and advantages of the invention will become more apparent during the course of the following description, particularly when taken in connection with the accompanying drawing.

In the drawing, wherein like numerals are employed to designate like parts throughout the same:

10 The single view illustrates apparatus suitable for practicing the method of the present invention.

Briefly stated, the method of this invention comprises withdrawing from the plating tank a predetermined quantity of relatively warm solution and passing said solution into evaporator means which may be in the form of a vacuum chamber. The solution is caused to boil within the evaporator means to a degree sufficient to produce a liquid portion of substantially reduced temperature. The lower temperature liquid received from the evaporator means is returned to the plating tank, and in combination with the solution present therein, accomplishes a temperature reduction of the entire body of solution to the point desired for optimum plating conditions. The vapor portion produced in the evaporator means is passed to a condenser, and the condensate therefrom withdrawn and directed into a tank which may be employed for rinse or recovery purposes. Liquid in the rinse tank may be flowed into the plating tank to maintain the desired solution level therein.

30 Prior practice in the art, as has been noted, required shut down of the plating line during certain periods of the year, and in the figure there is illustrated apparatus by means of which this unsatisfactory condition is eliminated, and savings of approximately 55% of the plating

35 solution effected. While the structure shown has proven particularly effective in recovering substantial quantities of chromic acid plating solutions and will be described in that connection herein, it will be appreciated that the features of this invention are not restricted to a chromium plating bath and may be utilized with other known plating solutions presenting similar problems of temperature control.

40 In accordance with the principles of this invention, there is located in the tank 10 of the figure a feed line 12 to withdraw high temperature plating solution from said tank. Provided for the purpose of returning reduced temperature liquid to the tank is a return line 14. One end of each of the lines 12 and 14 is submerged in the plating solution, and experience to date has indicated 45 that a depth of between fourteen and eighteen inches is generally satisfactory.

To provide a positive flow of relatively warmer solution from the tank 10 to evaporator means 16, there is 50 preferably located in the line 12 a feed pump 18 which may be of the electrically driven centrifuge type. A similar pump 20 is utilized in the return line 14 to increase the flow of cooled liquid from the evaporator 16 to the tank 10; however, gravity may be adequate for this purpose in certain installations.

55 While the solution temperature desired will vary under particular plating conditions, by way of specific example, it is customary in plating 0.01 mil of chromium on steel with a 33 oz. per gallon bath that said bath come to equilibrium at approximately 120° F. at a current density of two amperes per square inch and a plating time of six minutes. During electrolysis, however, the temperature of the plating solution may rise well above 120° F., and may be more in the order of 140° F. or more. Cold water from the municipal supply system is accordingly circulated through cooling coils in the tank; however, in many regions during the hot summer months water from

the cold tap may reach a temperature of 85° F. and therefore have rather poor coolant qualities.

To maintain a typical chromium plating bath at equilibrium with a temperature not substantially more than 120° F. under the other conditions noted, relatively warm solution is withdrawn from the tank through the feed line 12 and evaporated sufficiently to remove an amount of heat therefrom such that the cooled liquid returning to the tank through the line 14 will have a temperature generally around 100 to 102° F. Since conditions within the evaporator means 16 may have to be changed under variations in the temperatures of the liquid carried by the lines 12 and 14, indicating means 22 and 24 are located in said lines to obtain liquid temperature readings therefrom.

The evaporator means 16 may take any one of a number of different forms known to the art, and one construction which has proven quite effective in actual practice is a vacuum chamber of the barometric flash type. The chamber 16 is designed to receive and return a fluid flow of approximately 2200 gallons per hour, and by a reduction of pressure within said chamber, causes a flash-off of low temperature steam to accomplish a temperature reduction of from about 120° F. to approximately 100° F. A vacuum pump 26 of proper capacity is in communication with the evaporator chamber 16 to reduce the pressure within said chamber, generally to around 27.5 inches of mercury, to readily cause boiling of the relatively warm solution supplied thereto. Thus, by utilizing the latent heat of vaporization of the plating solution, the desired temperature reduction is accomplished.

Steam or vapor generated during the boiling process within the evaporation chamber 16 may be received in line 28 extending outwardly from the upper portion of the chamber and in communication with a condenser 30 by passage through one wall thereof. The condenser 30 may be of any suitable evaporative type, and is preferably provided interiorly thereof with cooling coils 32 to convert the vapor into a liquid state. Components customarily forming a part of an evaporative condenser, and including such means as a blower motor, spray pump, and the necessary water, thermostatic and drain valves, are associated with the condenser construction shown. In addition, a temperature indicating device 34 is normally included to obtain steam temperature readings.

Condensate produced in the chamber 30 is removed therefrom by a vacuum pump 36 located in the line 38 which terminates in a tank or other structure 40 providing a rinse or recovery point for the condensate. The tank 40 is located in proximity to the plating tank 10, and there is provided a return line 42 having a pump 44 therein to flow rinse solution to the plating tank to maintain the desired level therein, as determined by a level control device 46 in said tank 10. It should be mentioned in this connection that the prior practiced procedure has been to dump the rinse tank solution into the drain when a particular concentration of chromic acid was found to be present therein. Now, however, by pumping relatively pure condensate into the rinse tank, the chromic acid concentration therein is maintained at a sufficiently low point that frequent pumping is not required. In addition, since a small amount of chromic acid invariably exists in the rinse tank 40, this may be pumped into the plating bath and used to restore the liquid level to the desired point, that is, to replace solution taken therefrom on the work pieces and other such losses. Rinse solution is thus no longer wasted, and said solution used for a valuable purpose in the plating tank when the chromic acid concentration in the rinse becomes too high. This however, never reaches a critical point since the rinse solution is diluted by condensate from the line 38. Preferably, the intake for the line 42 is located adjacent the bottom of the rinse tank to receive chromic acid present therein.

It may be seen from the foregoing that there is provided by the present invention method and apparatus which effectively maintains the temperature of a plating solution at any level desired. The structure shown may incorporate temperature control and other electrical means to the end that a predetermined increase in the solution temperature in the feed line 12 from the tank will automatically initiate withdrawal of solution and evaporation thereof to accomplish a heat reduction and return of cooled liquid to the tank 10. Each of the components of the system are relatively simple in construction and operation, and the plating procedure may continue uninterrupted during the removal of relatively warm solution and return of cooled liquid. Minor additions of chromium trioxide and catalyst may be required from time to time to revitalize the plating solution; however, this is customarily accomplished with little interference to the plating operation.

Pursuing the principles of this invention, it is no longer necessary to waste by drainage substantial quantities of rinsing solution, nor to cause potential damage to a sewage system by passage therein of relatively high concentration rinse solution. Further, and probably of prime importance, a close down of the plating operation is no longer necessary as was required when solution temperature could not be brought down sufficiently by earlier heat exchange techniques. Experience in actual practice has indicated that quantities of plating solution approaching 55 or more percent can be saved by practice of the herein disclosed method, and this is particularly true during the warmer months of the year.

It is to be understood that modifications may be effected in the processes and structures herein disclosed without departing from the spirit of the invention or the scope of the subjoined claims.

I claim as my invention:

1. A method of equalizing the temperature of a plating bath having relatively warm aqueous plating solution therein, which includes the steps of passing the relatively warm solution into an evaporation zone and removing heat from said solution by boiling while generating vapors therefrom to substantially reduce the temperature of the solution, passing the reduced temperature solution directly into the plating bath at essentially the temperature resulting from the heat removal in the evaporation zone, removing the vapors from the evaporation zone and directing said vapors into a condensation zone, and removing the condensate from the latter zone and receiving the same in a collection zone.
- 40 2. A method of equalizing the temperature of a plating bath having relatively warm aqueous plating solution therein, which includes the steps of passing the relatively warm solution into an evaporation zone and removing heat from said solution while generating vapors therefrom to substantially reduce the temperature of the solution, passing the reduced temperature solution into the plating bath, removing the vapors from the evaporation zone and directing said vapors into a condensation zone, removing the condensate from the latter zone and receiving the same in a rinse bath, and passing rinse solution from the latter bath into the plating bath to maintain the desired level therein.
- 55 3. Apparatus for cooling plating solutions, comprising a tank containing plating solution, a vacuum chamber for boiling said solution to reduce the temperature thereof and having a solution inlet and outlet and a vapor outlet, tubular means connected to the tank at one end and at their opposite ends to the solution inlet and outlet, means for pumping relatively hot solution from the tank through the tubular means to the chamber, means for pumping relatively cool solution from the chamber, through the tubular means to the tank, a vapor condenser, tubular means connected to said condenser and the chamber vapor outlet directing solution vapors from the chamber to the condenser, a tank normally containing rinse
- 60
- 70
- 75

solution, means for removing condensate from the condenser and passing the same to the rinse tank, and means pumping rinse solution from the rinse tank to the plating tank maintaining the desired level in the latter tank.

4. Apparatus for cooling plating solutions, comprising a tank containing aqueous plating solution of relatively high temperature, an evaporation chamber for reducing the temperature of a solution passed therein and provided with a vapor outlet, tubular connecting means between the tank and chamber simultaneously removing relatively high temperature solution from the tank and directing relatively cool solution thereto, a rinse tank communicating with said plating tank, and condenser means communicating with said vapor outlet in the evaporation chamber and with the rinse tank receiving vapor from said chamber, condensing said vapor and directing the condensate to the rinse tank for mixture with the solution therein and transfer to the plating tank to maintain a desired level therein.

5. A method of controlling the temperature of a plat-

10 15 20

ing bath, which comprises withdrawing from the bath a quantity of relatively high temperature aqueous plating solution, removing heat from said solution by boiling, separating said solution into aqueous vapor and aqueous liquid solution portions both having a lower temperature than said relatively high temperature aqueous plating solution, removing and condensing the vapor portion, and passing the liquid portion to the plating bath to reduce the temperature thereof, while directing the aqueous condensate first to a rinse bath and then to the plating bath in admixture with rinsing solution.
